(57) CLAIM

The ornamental design for a bowl as shown and described.

DESCRIPTION

FIG. 1 is a front elevation view of a bowl according to my new design;

FIG. 2 is a bottom plan view thereof; and,

FIG. 3 is a top plan view thereof.

The gray-shaded portions of the bowl represent a contrast in appearance.

The broken lines shown in the drawings depict portions of the bowl that form no part of the claimed design.

The dash-dot-dash broken line defines a boundary of the claimed design and form no part of the claimed design.
